DESIGN FOR A CRIBBAGE BOARD

Rhys Orville Evans, St. Paul, Minn.

Application February 13, 1947, Serial No. 136,895

Term of patent 14 years

(Cl. D34—5)

To all whom it may concern:

Be it known that I, Rhys Orville Evans, a citizen of the United States, residing in St. Paul, county of Ramsey, and State of Minnesota, have invented a new, original, and ornamental Design for a Cribbage Board, of which the following is a specification, reference being had to the accompanying drawings, forming part thereof.

I claim:

The ornamental design for a cribbage board, as shown.

RHYS ORVILLE EVANS.
